MOTORIZED BURNER CONTROLLER

Benjamin Cyr, Minneapolis, Minn., assignor to
 Minneapolis-Honeywell Regulator Company,
 Minneapolis, Minn., a corporation of Delaware

Application November 17, 1938, Serial No. 240,979

15 Claims. (CL. 137—144)

- The present invention is concerned with a motorized burner controller and more particularly with a motorized fuel valve having provision for operating a secondary air damper.
- 5 In the copending application of Sylvanus C. Shipley, Serial No. 753,557, which has matured into Patent No. 2,159,624, issued May 23, 1939, there is disclosed a motorized fuel valve in which the motor actuates not only the valve but also 10 an arm which projects outside of the motor housing and is connected to a damper controlling the admission of secondary air to the furnace. This prior application is primarily concerned with the provision of means whereby the valve may not 15 be opened by manipulation of the secondary air damper. In the arrangement of this prior application, this is accomplished by the provision of a stop for the arm which is not effective when the valve is lifted by the motor.
- 20 An object of the present invention is to provide a motorized fuel valve with an associated secondary air damper arm movable with the valve in which improved means are provided for preventing the valve from being opened by manipulation of the secondary air damper arm.
- 25 A further object of the present invention is to provide an arrangement such as set out in the previous object in which the means for preventing the valve from being opened by the secondary 30 damper arm consists of a strain release connection between a portion of the damper arm and the valve.
- 35 A further object of the present invention is to provide an arrangement such as set forth in the previous object in which means are provided for preventing opening of the valve by the motor if the strain release connection is extended.
- 40 A still further object of the present invention is to provide a motorized valve in which the motor unit is mounted with respect to the valve so that the former may be selectively swivelled with respect to the latter.
- 45 A still further object of the present invention is to provide a motorized valve in which the power unit can be removed from the valve without opening of the valve.
- 50 A still further object of the present invention is to provide a motorized valve in which the power unit is secured to the valve by means including only one threaded fastening member.
- 55 Other objects of the invention will be apparent from a consideration of the accompanying specification, claims, and drawings, of which:
- 60 Figure 1 is a vertical sectional view of the

control valve assembly taken substantially on the line 1—1 of Figure 2;

Figure 2 is an end elevational view of the same looking from the right in Figure 1 and showing the cover in section along the line 2—2 of Figure 3;

Figure 3 is a side elevational view looking towards the right in Figure 2, a portion of the mechanism being shown in section along the line 3—3 of Figure 2;

Figure 4 is a diagrammatic view of the structure shown in Figures 1 to 3 embodied in a burner control system;

Figure 5 is a vertical sectional view of a portion of a modified form of the invention, and

Figures 6 and 7 are further showings of portions of other species of the invention.

Referring now to Figures 1 to 4, the control valve generally designated at 9 has a valve casing 10 having inlet and outlet openings 11 and 12 respectively. The valve casing 10 has a transverse wall 13 having a port opening 14 therein which is encompassed by an annular shoulder to form a valve seat 15. The valve member comprises a valve disc 16 adapted to seat on the annular seat 15, reinforcing washers 17 and 18 flanking the valve disc 16, said valve disc 16 and said reinforcing washers 17 and 18 being securely clamped together by means of a plug 19 and a nut 20 screwed thereon.

Extending into the plug 19 of the valve member is a valve stem 21, the plug 19 and the valve stem 21 having holes to receive a pin 22 to secure the valve stem 21 and plug 19 together in fixed relation. The stem 21 is slidably mounted in a sleeve guide member 23 which is secured to a cup-shaped supporting member 24. Located beneath the lower surface of the cup-shaped member 24 are a disc 25, a packing washer 26 and a second disc 27. The assembly consisting of the discs 25, 26 and 27 are secured together and to the cup-shaped supporting member 24 by means of rivets 28. A screw thimble clamping nut 29 holds the support 24 in fixed relation to the valve casing 10.

In order to effectively seal the valve casing 10 against leakage of fluid therefrom, a diaphragm 31 is secured to the upper end of the valve stem 21 by clamping the diaphragm 31 between a nut 34 and a washer 35, the clamping action being effected by a nut 36 screwed on the screw threaded portion 33 of the valve stem 21. The outer edge of the diaphragm 31 is clamped between the support 24 and a power unit base member 38 by means of screws 39.

Mounted on the base 38 by any suitable fas-

tenting means (not shown) are two upright, spaced parallel plates 40 and 41 (as best shown in Figure 2), the plates 40 and 41 being held in spaced relation by bolts 43 cooperating with nuts 45 to clamp the plates 40 and 41 against spacer members 44.

A motor, generally designated at 46, is secured to and spaced from the vertical plate 40 by means of screws 47 and spacers 48. The motor shaft 10 extends through the plate 40 and has a motor pinion 49 located on the end thereof (as shown in Figure 1). Located between the plates 40 and 41 and driven by the motor pinion 49 is a reduction gear train, comprising a gear 50 engaging the motor pinion 49, a gear 52 engaging a pinion 51 integral with the gear 50, and a gear 54 engaging a pinion 53 integral with the gear 52. The gears and pinions are suitably mounted and spaced between the upright parallel plates 40 and 41.

Surrounding the operating mechanism of the valve is a cover member 58. This cover member slidably engages the base member 38 and is held in position by a nut and bolt assembly 59 which is secured to an upper curved portion of the supporting plate 40.

A lever assembly generally designated by the reference numeral 61 is pivotally mounted upon a spacer 63 journaled on a pin 64 extending between the two plates 40 and 41. Pivotally secured to an intermediate portion of the lever assembly 61 by a pin 65 is a yoke member 66, which yoke member surrounds and is adapted to engage the base portion of a second yoke member 62 screw threaded to the upper end of the valve stem 21. The yoke member 62 bears at its upper end against the under side of pivot pin 65. Pivotally secured to the left-hand end of the lever assembly 61, as viewed from Figure 1, is a member 67 which is provided with a hook 68 adjacent its upper end. This hook 68 is adapted to be engaged by a pin 69 secured to and movable with gear 54 of the gear train. A coil spring 70 surrounds the pivot pin 71 which connects member 67 to the lever assembly 61 and serves to bias the member 67 into engagement with a pin 73 secured to plate 40. The biasing of member 67 against pin 73 serves to maintain it in such a position that the hook 68 lies in the path of the pin 69. Upon energization of the motor, the gear 54 is rotated in a clockwise direction causing the pin 69 to engage the hook 68 and lift member 67 upwardly. The upward movement of member 67 causes a clockwise movement of the lever assembly 61 with the result that yoke member 66 is moved upwardly and engages and lifts yoke member 62 so that valve stem 21 is lifted upwardly, moving the valve to open position.

The structure which has so far been described is in most respects similar to the apparatus of the above mentioned Shipley application. In this Shipley application, there was only one lever member corresponding to the lever assembly 61. In the present structure this lever assembly comprises two members 80 and 81 which are pivotally joined by a pivot member 82. A biasing spring 83 is secured at its lower end to the lever member 81 and at its upper end to the spacer member 44. The left end of the lever member 81 is provided with a hook portion 84 which is adapted to rest on the spacer 63 which forms part of the pivotal mounting of the lever assembly 61. It can be readily seen that the spring 83 serves to urge lever 81 in a counter-clockwise direction so that the hook portion 84 is firmly pressed against

the spacer 63. By reason of this engagement of hook portion 84 with spacer 63, the two members 80 and 81 are held in rigid relation as though they constituted a single member. Spring 83, furthermore, not only tends to hold members 80 and 81 in rigid relation to each other but also tends to rotate the entire lever assembly 61 about the pivot constituted by spacer 63 and hence to bias the valve 9 to closed position.

The two lever members 80 and 81 functioning together as a unit, are used to control the position of a secondary air damper as will be pointed out in more detail later. For this purpose, the member 81 is provided with a plurality of holes 86 for the application of a suitable connecting member 89 between the lever member 81 and a secondary air damper 90 (show in Figure 4). As will be noted from Figure 4, the species of the invention shown in Figures 1 to 4 is particularly adapted for use with a secondary air damper 20 which is biased to an open position and is permitted to move to open position upon opening of the valve. This form of secondary air damper is quite desirable inasmuch as it insures that if anything happens to the connecting means 89, 25 the secondary air damper will go to the open position, which is the safe position.

While the two lever members 80 and 81 normally function as though they were a single unit, it is impossible to open the valve by manipulation 30 of member 81. As pointed out in connection with the aforementioned Shipley application, it is quite undesirable for the average layman to be able to manually open a gas valve. If it is possible for him to readily open the valve, he will do so in the event of power failure, often when the pilot burner is not lighted. The result is that a very serious explosion is apt to be produced upon subsequent ignition of the pilot burner. As pointed out about, in the previous application a 35 stop is provided to prevent the member corresponding to hook member 67 from being moved upwardly by manual operation of the horizontal lever. In the present invention, this is accomplished by reason of the strain release connection provided between members 80 and 81, including the pivotal connection therebetween and the biasing spring 83. It will readily be apparent that if an attempt is made to open the valve 81 from outside of the cover 58, such attempt will 40 result only in the rotation of lever 81 in a clockwise direction. Hook 84 will merely move away from spacer 63 and there will be no movement whatsoever of lever 80. It will be noted that the spring 83 which is the biasing spring for the 45 valve also serves as the spring means for the strain release connection between the two lever members 80 and 81. Thus with the construction of the present invention it is unnecessary to provide any stop whatsoever, since movement of 50 lever 81 in valve opening direction has no effect upon the position of the valve.

The service man or other person familiar with the valve construction can very quickly open the valve if it is desired to do so in the event of 55 power failure. All that it is necessary to do to open the valve is to move the nut of the clamping assembly 59, and then remove the cover 58. The left-hand end of lever member 80 is provided 60 with a finger piece 92 whereby the lever 80 can be conveniently located in a clockwise direction by pulling up on this finger piece. Means are provided for maintaining the valve in open position in the event of power failure. This means 65 consists of a pin 94 (best shown in Figure 2), 70

which is journaled in the plate 41 and is adapted to be moved inwardly underneath the lever 80. The pin 94 is biased to open position by spring 96 interposed between plate 41 and a collar 97 of insulating material secured to pin 94. When pin 94 is moved inwardly against the bias of spring 96, the action of biasing spring 83 on the lever assembly 61 serves to frictionally hold the pin 94 in its inner position against the action of biasing spring 96. Upon any further upward movement of the lever assembly 61, by the motor, for example, the spring 96 is effective to immediately return the pin 94 to the position shown in the drawing (Figure 2).

15 Cooperating with pin 94 are a pair of recycling contacts 98 and 99. The recycling contact 99 is carried by a rigid support 100 as best seen in Figure 3, this support being secured to insulating plate 135. The contact 98 is carried by a flexible contact blade 101, the end of which lies in the path of movement of the insulating collar 97. The flexible contact member 101 is biased in the direction of contact member 100 so as to tend to move contacts 98 and 99 in engagement. As long as pin 94 is in the position shown in Figure 2, contacts 98 and 99 are out of engagement by reason of the insulated collar 97 engaging the end of flexible contact member 101. As soon, however, as pin 94 is moved inwardly, contact members 98 and 99 are allowed to move into engagement with each other. The purpose of this will be discussed in more detail later.

In connection with the means for preventing manual opening of the valve by manipulation of lever 81, I have further provided means to prevent opening of the valve by the motor if the strain release connection is extended. If some such means as this is not provided, it would be possible for the installer to pull down the lever 81 for connecting the same to the damper 90. This extension of the connection between members 80 and 81 could be carried to a point such that movement of the member 80 in valve opening direction would have no effect upon the position of lever member 81. The result would be that the secondary air damper 90 would remain closed so that the burner would be operated with inadequate air to properly support combustion.

50 I have accordingly found it desirable to find some means for preventing operation of the valve by the motor if lever 81 is pulled downwardly when the valve is in its closed position.

Pivotedly secured to the spacer 44 is a member 55 105 which if otherwise unrestrained will be moved by gravity into a position where the outer end thereof engages the teeth of gear 54. Such movement of lever 105 is normally prevented by link 106 which is forked at its upper end to provide two spaced leg portions 107 and 108. These leg portions 107 and 108 straddle a spacer member 44 and guide the link member 106. At its lower end the link member 106 is similarly bifurcated and the two legs at the lower end also straddle a spacer member 44. As best seen in Figure 2, the upper end of the leg 107 of link 106 is provided with a shoulder portion 108 which overhangs and engages a shoulder portion 110 of the pivoted member 105. Link member 106 is normally biased downwardly by means of a spring 112. The spring 112 is secured at its lower end to a lower spacer member 44 and at its upper end to the leg 107 of link 106. The link 106, by reason of being biased downwardly, serves to maintain pivoted member

105 in the position shown in Figure 1, in which position, the same is free of the teeth of gear 54. As soon as link member 106 is raised, however, the biasing action imparted to member 105 is eliminated and this member drops by gravity into a position in which it engages the teeth of gear 54. As indicated in dotted lines in Figure 1 and as shown in full lines in Figure 2, link 106 is provided with a portion 115 bent at right angles to the main portion thereof. This angularly extending portion 115, as best shown in Figure 1, rests upon the lever assembly 61 at a point immediately above the spacer 63 on which the lever assembly 61 is pivoted.

When the lever assembly 61 is rotated by reason of operation of the motor, such rotation occurs about the spacer 63 so that the vertical position of the upper edge of the lever assembly at this point is not appreciably changed. The result is that link member 106 is not moved upwardly when the lever assembly 61 is rotated as a unit by reason of operation of the motor. If the lever 81 is manually rotated independently of lever 80, however, such rotation occurs about the pivot pin 82. The result is that the upper edge of the hook portion 84 of lever 81 is raised vertically so as to move link member 106 upwardly and thus release the biasing action of spring 112 on member 105. This permits the member 105 to drop into engagement with the teeth of the gear 54, as previously explained. Thus if the installer should, in connecting the lever 81 with the damper 90, place too much tension upon the connecting member 89, it will be impossible for the motor to open the valve. Since it is the universal practice of those installing gas heating equipment to start the burner up by operation of the valve motor as a final test of the system, such faulty connection of the secondary air damper will be discovered before the installation man leaves. With this arrangement, it is accordingly impossible for the arm 81 to be left in the position such as to prevent complete opening of the secondary air damper.

In those cases in which it is desired to be able to operate the valve from the exterior of the cover member 58, a pair of aligning holes are provided in members 80 and 81 at 104. One of these two holes is threaded so that a screw may be inserted through the other hole and secured in the threaded one. As soon as this screw is secured in the two holes, the two lever members 80 and 81 function at all times as a single unit. It is thus possible to supply the valve with or without the feature above discussed, the only change necessary being the removal of a screw.

It is often desirable to have other apparatus in addition to the secondary air damper controlled in accordance with the position of the valve. Thus in certain systems it is desirable that a circulating fan motor be turned on when the valve is opened. Provision is accordingly made for the closing of a switch simultaneously with the opening of the valve. For this purpose, a link member 127 is pivotally mounted on the pivot pin 71. This link member 127 extends up a portion of its distance between supporting plates 40 and 41 and at an intermediate point is provided with a U-shaped portion 128 extending around the plate 41. The remaining portion of the link 127 extends outside of the plate 41 and is connected to a second link 130 which is pivotally secured at 131 and is provided with a mercury switch carrier 132 in which is disposed

a mercury switch 133. The construction of the mercury switch is entirely conventional and in the modification shown in the drawings, the mercury switch is so disposed that upon tilting in a clockwise direction the switch is moved from open circuit to closed circuit position. Inasmuch as the pivot pin 71 is secured to lever member 80 and is hence moved upwardly upon opening of the valve, it will be apparent that upon opening of the valve, lever 130 is rotated in a clockwise direction to cause closure of switch 133.

As pointed out previously, the contact bars 100 and 101 are carried by the insulating plate 135. This plate is rigidly mounted on and in spaced relation to plate 41. The contact member 100 which, as previously pointed out, is relatively rigid, is provided at its upper end with a contact 136. This contact is adapted to cooperate with a contact 137 carried by a lever 138 pivotally supported at 139. The lever 138 has rigidly secured thereto an arm 140 which extends upwardly to the right and is provided with a slot 141. Extending through the slot 141 is a pin 142, which pin is secured to a disc 143. Disc 143 is rotatably mounted upon a shaft 144, the same shaft upon which gear 54 is secured. Disposed on each side of the disc 143 are washers 145 of friction material. Non-rotatably secured to shaft 144 is a cam disc 146. The disc 146 is non-rotatable with respect to the shaft 144 by reason of the fact that at the point upon which the cam disc 146 is mounted the shaft has one side flattened, as indicated in Figure 3. Cam disc 146 is, however, 35 slidable upon the shaft. Located adjacent to the cam disc 146 is a collar 148 which collar is also slidably mounted upon shaft 144. Secured on shaft 144 adjacent the outer end thereof is a cup-shaped member 149 and between this cup-shaped member and the collar 148 there is disposed a biasing spring 150. This biasing spring serves to urge collar 148 and consequently cam disc 146, washer 145 and the disc 143 towards the right, urging these various members into engagement 45 with each other. By reason of the placing of the friction washers 145 on each side of the disc 143, this disc is frictionally mounted on the shaft 144.

Referring now to Figure 3, it will be evident that a clockwise rotation of shaft 144 will tend to rotate disc 143 in a clockwise direction. Such clockwise rotation of disc 143 will cause the pin 142 carried thereby to engage the upper edge of the diagrammatically extending slot 141 and thus to rock the lever 138 in a counter-clockwise direction. This will result in engagement of contacts 136 and 137, this engagement taking place after a very slight initial movement of shaft 144. After these contacts have engaged, it is no longer possible for disc 143 to rotate so that this member slips with respect to shaft 144 as the latter member continues to rotate in a clockwise direction.

The cam disc 146 is provided with a notch 153, which notch is adapted to assume a vertical position when the valve reaches full open position. The cam 146 is adapted to cooperate with a switch blade 154, which switch blade carries a pair of contacts 155 and 156. The switch blade 70 154 is, in turn, adapted to cooperate with a composite switch blade comprising a relative rigid member 157 and a somewhat flexible member 158 secured to member 157. The rigid member 157 carries a contact 161 and the flexible member a contact 162. The contact carrying members are

so disposed and the contacts 155 and 156 are of such length that contact 155 moves into engagement with the contact 162 slightly before contact 156 moves into engagement with contact 161. The two sets of contacts are connected in parallel, the two sets being provided for the purpose of giving additional insurance that the circuit controlled thereby will be closed. In other words, under all ordinary circumstances the engagement of contacts 155 and 162 will close the circuit. If for any reason, however, these contacts should be slightly corroded then the circuit will still be closed by contacts 156 and 161.

As indicated earlier, the cam 146 has a notch 153 which assumes a vertical position when the valve reaches open position. The left-hand end of switch blade 154 is formed in the shape of a cam follower which is adapted to drop down into the notch 153. Thus when the valve reaches open position, switch blade 154 moves downwardly causing separation of both contacts 155 and 156 from their respective associated contacts. The function of the switching mechanism which has just been described, including contacts 155, 156, 162 and 161, is to control the energization of the lifting winding of motor 46. This motor has both a lifting and a holding winding and when the valve reaches the top of its stroke it is desirable that the lifting winding be de-energized to reduce the consumption of power 30 by the motor.

In Figure 4, a burner control system is shown employing the improved mechanism of the present invention. In this figure, the apparatus is shown in somewhat schematic form to give a clearer idea as to the electrical connections between the various elements thereof and between these elements and the rest of the control apparatus.

The motor 46, previously referred to, is shown in this figure as comprising a rotor 164 and a plurality of windings 165 and 166. The winding 165 is a holding winding whereas the winding 166 is a lifting winding. Power for the operation of the system is supplied by a step-down transformer indicated by the reference numeral 175. This transformer comprises a high voltage primary 176 and a low voltage secondary 177. The primary 176 is connected to line wires 178 and 179 leading to a suitable source of power, not shown.

The operation of the system is controlled by a room thermostat generally indicated by the reference numeral 183. This thermostat comprises a bimetallic element 184 to which are secured contact arms 185 and 186 adapted to cooperate with contacts 187 and 188 respectively. The spacing between contact arm 185 and contact 60 187 is slightly less than that between contact arm 186 and contact arm 188. Thus when the contact arms 185 and 186 are moved to the left by the cooling of bimetal 184, engagement will first be effected between contact 187 and contact arm 185, then between contact 188 and contact arm 186.

As previously indicated, the switch 133 can be used for the control of a fan motor. This fan motor is used in a forced warm air system for driving an air circulating fan to provide forced circulation of heated air to the space being heated. This fan motor is indicated in Figure 4 by the reference numeral 190.

Operation

The various elements are shown in the posi-

tion occupied when the temperature adjacent to thermostat 183 is at or slightly above the desired value. Let it be assumed that this temperature begins to fall so as to cause engagement first of contact arm 185 with contact 187 and then of contact arm 186 with contact 188. No circuits are established until arm 186 engages contact 188. As soon as such engagement does take place, however, a circuit is established to the holding 10 winding 165 of motor 46 as follows: from the upper end of transformer secondary 177 through conductors 192 and 193, contact 187, contact arms 185 and 186, contact 188, conductors 195 and 196, holding winding 165 and conductor 197 to the 15 other end of secondary 177. At the same time, a circuit is established to the lifting winding 166 as follows: from the upper end of secondary 177 through conductors 192 and 193, contact 187, contact arms 185 and 186, contact 188, conductors 195 and 196, lifting winding 166, conductor 198, switch blade 154, contacts 155, 156, 162 and 161, switch blade 157, and conductor 199 to the other terminal of secondary 177.

The establishment of these two circuits to field 25 windings 165 and 166 will cause rotation of the motor 164, which acting through the gear train, causes a rotation of gear 54 in a clockwise direction. The rotation of gear 54 in a clockwise direction causes cam disc 146 and disc 143 to also 30 rotate in a clockwise direction as indicated by the arrows adjacent these members. The initial rotation of disc 143 causes closure of contacts 136 and 137. The closure of these two contacts causes a holding circuit to be established to the two 35 field windings 165 and 166. Considering the lifting winding 166, the circuit thereto is as follows: from the upper end of secondary 177 through conductors 192 and 193, contact 187, contact arm 185, bimetal 184, conductor 200, contacts 136 and 40 137, lever 138, conductors 201, 202 and 196, lifting winding 166, conductor 198, switch blade 154, contacts 155, 156, 162 and 161, switch blade 157 and conductor 199 to the other terminal of secondary 177. Inasmuch as it is obvious that as long as 45 the switch including switch blades 154 and 157 is closed, the two windings 165 and 166 are connected in parallel, it is believed unnecessary to also specifically trace this circuit to field winding 165.

50 It will be noted from the foregoing description that the closure of contacts 136 and 137 causes a circuit to be established for field windings 165 and 166 which is independent of the engagement of contact 186 with contact 188. Thus the motor 55 will not become deenergized until contact arm 185 has separated from contact 187. In this manner, a temperature differential is required between the opening and closing of the valve and it is assured that a chattering action will not result when the contact arm 186 first insecurely engages contact 188.

The rotation of gear 54, as previously explained, causes the pin 69 to engage the hook 68 raising member 67 upwardly. The upward movement of member 67 causes the lever assembly 61 to rotate about the bushing 63, moving the valve to open position.

At the same time that the member 67 is moved upwardly, the link 121 will also be moved upwardly to cause rotation of lever 138 in a clockwise direction. This rotation of lever 138 causes closure of mercury switch 133 with the result that a circuit is established to the fan motor 190 as follows: from line wire 178 through conductor 204, 55 mercury switch 133, conductor 205, fan motor 190

and conductor 206 to the other line wire 179. It is thus assured that the fan motor 190 will be energized simultaneously with the opening of the valve.

As soon as the valve has reached fully open position, the cam follower of switch blade 154 drops down into the notch 153 of cam disc 146 permitting the switch blade 154 to move away from switch blade 151 causing separation of the associated contacts. This results in the circuits previously traced through lifting winding 166 being interrupted so that the holding winding 165 is the only winding which is now energized. By providing two windings and deenergizing one of these windings, the consumption of power during the time that the valve is open is considerably reduced. This not only results in a reduction in the cost of operation but also insures that the motor will not overheat and cause sticking of the bearings. It is to be understood that it is highly necessary that the bearings of the motor do not stick to even the slightest extent since a small resistance offered to the turning of the motor rotor when amplified through the gear train will exert considerable opposition to movement of the lever assembly 61 in valve closing direction by the biasing spring 83.

Under normal operation, the valve will stay open until the thermostat is satisfied, that is, until contact arm 185 separates from contact 187. When this takes place the energizing circuit to holding winding 165 will be interrupted with the result that the motor is completely deenergized. The spring 83 is now able to rotate the lever assembly 61 in a counter-clockwise direction and thus move the valve to closed position.

As indicated in the earlier portion of the specification, it is often desirable for an experienced operator to move the valve to open position and maintain the valve in this position. This is particularly necessary during a prolonged power failure or when the heating equipment is to be operated during the construction of a building and prior to the installation of electrical wiring therein. As also indicated earlier, this is done by removing the cover 58, grasping the finger piece 92 and rotating the lever assembly 61 in a clockwise direction. When the valve is in substantially open position, the pin 94 is moved inwardly so that the inward end of this pin rests underneath the lever assembly 61 and holds the same in a position corresponding to substantially valve open position. It is to be understood that the valve is not as completely open, however, as it is when the same is moved to open position by reason of operation of the motor. The moving of pin 94 inwardly, it will be recalled, caused the closure of contacts 98 and 99. These contacts are indicated schematically in Figure 4. Closure of these two contacts results in a circuit being established to the motor which is independent of the thermostat 183, the circuit to lifting winding 166 being as follows: from the upper end of transformer secondary 177 through conductors 192 and 208, contacts 98 and 99, conductors 209, 202 and 196, lifting winding 166, conductor 198, switch blades 154 and 157 and their associated contacts, and conductor 199 to the other terminal of secondary 177. In view of the fact that the valve is not in fully open position, switch blades 70 154 and 157 will be in contact engaging position. It is believed unnecessary to trace the circuit to holding winding 165 under these conditions inasmuch as it is obviously connected in parallel with field winding 166. The presence of these en-

ergizing circuits for the field windings results in the motor being energized as soon as power is restored, causing the valve to be moved towards fully open position. The further movement of the lever assembly 61 releases the pressure upon pin 94 and allows this pin to return to the position shown in Figure 2 in which it is out of the path of lever 61. The returning of pin 94 to the position to which it is biased also results in the opening of contacts 98 and 99. The opening of these contacts results in the motor again being under the control of the thermostat and the valve either remains in open position or goes to closed position depending upon whether the thermostat is calling for heat or not.

It will be seen from the above that I have provided an improved valve and damper operating construction wherein it is impossible to open the valve by manipulation of the secondary air damper, this construction, moreover, being extremely simple in nature. It will further be seen that I have provided a generally improved motorized valve assembly for use in the control of a burner.

Species of Figure 5

25 In Figure 5, there is shown a form of my invention which is somewhat different than that of Figures 1 to 4 as regards the structure of the valve and the method of fastening the power unit 30 to the valve casing. Since the only difference between this form and that of Figures 1 to 4 is in this portion of the valve structure, the complete motor and valve assembly has not been shown in Figure 5.

35 Referring to Figure 5, the control valve which is generally designated by the reference numeral 209 has a valve casing 210 having inlet and outlet connections 211 and 212 respectively. Valve casing 210 has a transverse wall 213 having a port opening 214 therein which is encompassed by an annular shoulder to form a valve seat 215. A valve disc assembly corresponding to the members 16 and 17 of the previously described species is designated by the reference numeral 216. Placed 40 against the lower surface of this valve disc assembly is a reinforcing washer 218 and extending through the disc assembly is a plug 219 which corresponds to plug 19 of the previously described species. A valve stem 221 is secured to the plug 219 in the same manner as the corresponding elements are secured together in the previous species. A nut (not shown) corresponding to nut 20 of the previous species is threaded onto the plug 219 and serves to clamp the assembly together. Interposed between this nut and the valve disc assembly 216 is a diaphragm 237 and a cup-shaped washer 238. The entire assemblage including the valve disc 216 and its washer 218, plug 219, the diaphragm 237 and the washer 238 45 are securely clamped together by means of the nut previously mentioned. A guide sleeve 223 which is secured to a supporting member 224 serves to guide the movement of the valve stem 221. Supporting member 224 is clamped to the valve body 210 by means of screws 239. Interposed between the supporting member 224 and the valve body is the outer edge of the diaphragm 237. The outer edge of the supporting member 224 is curved upwardly and terminates in a narrow horizontally extending flange 225. Resting 50 on this flange 225 is a cup-shaped base plate 226 for the power unit. This base plate 226 is held in position on supporting member 224 by clamping strips 227. These clamping strips are provided with ears which extend through slots 228

in the downwardly extending flange of the cup-shaped base member 226. A screw 229 is associated with each of the clamping strips 227, extending through the base member 226 and screw threadedly engaging with the clamping strip 227. While only one such clamping strip 227 has been shown, it is to be understood that at least two of these will be provided at spaced points around the periphery of supporting member 224.

The power assembly is identical to that of the previously described species and comprises a pair of plates 240. Each of these plates 240 is provided at its lower left-hand corner with a tongue 241 adjacent which tongue 241 is a slot 242. The lower surface of the tongue 241 is slightly below the remaining lower surface of the plate 226. The base member 226 is provided with a pair of slots 243. Adjacent each of these slots 243, the material is struck up as at 244 to provide a cup-shaped recess for the ear 241.

The assembly including the two plates 240 is hingedly secured at one end by the tongues 241 projecting through the slots 243 and into the cup-shaped recess 244. At the other end, the power assembly is clamped downwardly by means of a bar 250 which extends between the two uprights 240 and is provided with a longitudinally extending flange 251. This flange is provided with an opening 252 through which a screw 254 extends. This screw 254 is threadedly engaged with the base member 226.

In assembly the power unit with the base plate 226, it is merely necessary to tip the power unit so as to permit the tongues 241 to enter their respective slots 243. The power unit is then tipped to resume its normally vertical position with the result that the tongues enter into the cup-shaped recesses 244 and so that the opening 252 is brought into alignment with the associated threaded opening in base member 226 for the screw 254. The screw 254 is then placed in position and tightened up with the result that by means of merely one screw the power assembly is securely fastened to the base member 226.

In many instances it is desirable to rotate the position of the power unit with respect to the valve. The position of the valve is of course determined by the direction of the gas line leading to the furnace. It often happens, however, that the secondary air damper, for example, may be in a position such that the power unit should desirably be turned. With the present modification this can be done in an extremely simple manner. All that it is necessary to do is to loosen the screws 229 which are associated with the clamping strips 227. When these screws are slightly loosened, the power unit can be readily turned with respect to the valve body, the stem 221 screwing into or out of the yoke member corresponding to yoke member 62. While it is true that the vertical position of the yoke member with respect to the valve stem is changed slightly, this is permissible due to the fact that this merely changes very slightly the position assumed by the lever assembly 61. Since the rotation would never exceed 360 degrees and since the pitch of the threads of stem 221 is relatively small this change in the annular position of lever 61 would never be enough to appreciably affect the operation of the valve.

It is often desirable in servicing operations to be able to conveniently replace one power unit with another. It is the power units which are more apt to eventually need repair and replacement. With the arrangement of the previous

species, it is necessary to shut off the gas to the system before the power unit is removed since it is impossible to remove the power unit without permitting gas to flow through the valve. In the modification of Figure 5, it is possible to remove one power unit and replace it without opening the valve. In order to do this all that it is necessary to do is to unscrew the clamping screws 229 and remove the clamping strips 227. Thereafter the power unit can simply be rotated until the yoke 62 has been screwed off of the valve stem 221. Since the pressure of the power unit is on the valve stem during this unscrewing operation there is no danger of the valve being opened. The yoke of the new power unit is then screwed onto the valve stem 221 and the clamping strips 227 are replaced and clamped in position. It will be readily apparent that this operation can be performed within but a few moments without at any time permitting the valve 209 to open.

It will thus be seen that with the arrangement of Figure 5, the assembly of the power unit to its base plate is accomplished with a minimum of screws and consequently in an extremely quick and simple manner. Moreover, with this species, the power unit can be quickly and easily rotated to any desired position with respect to the valve unit. Furthermore, the power unit can be readily replaced at any time without disturbing the closed position of the valve.

Species of Figure 6

In the previously described species, the valve unit was intended to be employed with a furnace installation in which the secondary air damper is biased to open position. This type of structure is commonly referred to as an indirect acting type inasmuch as during the pull on the secondary air damper occurs during the closing movement of the valve and is for the purpose of pulling the secondary air damper closed. In the direct acting type of installation, the secondary air damper is biased closed so that during the opening cycle both the valve and the secondary air damper are pulled open against their respective biasing means. In Figure 6, the lever assembly of a direct acting form of my invention is shown. This lever assembly is designated by the reference numeral 261 and comprises two levers 262 and 263 both of which are pivotally mounted at 264. As shown in Figure 6, lever 262 has its right-hand portion in front of lever 263. This lever portion is then moved upwardly at 266 and rearwardly at 267 and thence downwardly so that it extends in the rear of lever 263. The extreme left-hand end of the lever 262 is again bent forwardly so as to lie in the same plane as the right-hand end. This left-hand end is provided with openings 269 to which a chain 270 or other similar fastening means can be secured, such fastening means leading to a secondary air damper 271. It will be noted that the secondary air damper 271 is pivotally mounted at 272 and is biased by reason of its weight to closed position.

The lever 263 is the lever which is associated with the valve and with the actuating means. The yoke 66 is pivotally secured to this lever. Also secured to the lever is the member 67 which is provided at its upper end with a hooked portion 68 operated by a pin 69 carried by gear 54. The biasing spring 83 is secured to the extreme right-hand end of lever 262. This spring serves to rotate lever 262 in a counter-clockwise direction so as to cause the rearwardly extending portion 261 of lever 262 to bear against the upper

edge of lever 263. The spring 83 furthermore, acting through the rearwardly extending portion 267 of lever 262 and the lever 263, serves to bias the valve to closed position. The lever 262 is provided with an arcuate slot 275 through which 5 moves a pin 276 secured to the lever 263.

During normal operation of the system the clockwise rotation in gear 54 as a result of the energization of the motor, moves lever 67 vertically to rotate lever 263 in a clockwise direction. 10 Such clockwise movement of lever 263 lifts the yoke 66 and moves the associated valve to open position. The clockwise movement of lever 263 also serves to rotate lever 262 in a clockwise direction by reason of the upper edge of lever 263 15 bearing against the rearwardly extending portion 267 of lever 262. The secondary air damper 271 is thus also moved to open position. Upon de-energization of the motor, the biasing spring 83 is effective to rotate lever 262 in a counter-clockwise direction to close the secondary air damper 271. Such counter-clockwise movement of lever 262 also imparts to lever 263 a counter-clockwise movement to close the valve. 20

It will be understood that it is only the left-hand portion of lever 262 which extends outside of the power unit cover. If the user of the heating equipment attempts to open the valve by moving up on the lever 262 all that happens will be that the lever 262 will be rotated around the 30 pivot 264 against the biasing action of spring 83. The only way in which the valve can be opened is for the user to remove the cover and grasp the finger piece 280 at the left-hand end of lever 262. When this finger piece is moved upwardly the 35 entire lever assembly 261 is rotated in a clockwise direction in the same manner as during operation by the motor. The method of holding the valve in the open position, when manually moved there, is the same as in the species of Figures 1 40 to 4 and the mechanism for accomplishing this is not shown in this figure.

Species of Figure 7

In the species of Figure 7, I have shown a somewhat different form of lever assembly for use with a direct acting damper. This lever assembly which is generally indicated by the reference numeral 285 consists of two levers 286 and 287. The lever 286 is pivoted at 288 and is the lever 45 which forms the connection between the operating mechanism and valve. This lever is pivotally secured to the yoke 66 and has secured thereto the hook member 67. The biasing spring 83 is also secured to the right-hand end of this lever. 50 Thus upon upward movement of hook member 67, the lever 286 is rotated about the pivot point 288 to raise the yoke member 66 and hence move the valve to open position. The lever 287 is pivotally mounted on the pin 65 which pivotally connects the lever 286 to the yoke 66. The lever 287 is provided at an intermediate portion thereof with a forwardly projecting ear 289, which ear overhangs the upper edge of lever 286. The extreme left-hand end of lever 287 is bent forwardly 55 so as to bring the same into the plane of lever 286. Provided in this left-hand end are openings 291 for the reception of a chain or other fastening means for connecting the end with a secondary air damper (not shown). Interposed between the pivot point 288 and an ear 292 on the lever 287 is a coil spring 293. This spring 293 serves to bias the lever 287 in a counter-clockwise direction and thus to hold the ear 289 in engagement with the upper surface of lever 286. 60 70 75

During normal operation of the system, the upper movement of hook member 67, which as previously explained causes the lever 286 to be operated in a clockwise direction also serves to impart clockwise movement to lever 287 through lever 286. Such clockwise movement is imparted by reason of the upper edge of lever 286 engaging the ear 289 of lever 287. Upon deenergization of the motor, the biasing spring 83 serves to rotate the lever 286 in a counter-clockwise direction while the biasing spring 293 serves to cause the lever 287 to follow the lever 286. Thus during the normal operation of the valve the two levers 286 and 287 move as a unit, as in the preceding species.

If the user of the heating equipment attempts to open the valve by grasping the left-hand end of handle 281, which is the only portion projecting outside of the cover, the movement of lever 287 will have no effect other than to open the secondary air damper. Such movement of the lever will merely result in the same pivoting about pivot pin 65 against the tension of spring 293. Spring 293 is preferably of a type, which spring rate does not increase greatly as it is compressed. Moreover, the arrangement is such that the increase in spring rate is compensated for so that the action of spring 293 in tending to rotate lever 287 with respect to lever 286 is constant throughout the relative movement of lever 287 with respect to lever 286. It will be noted that as lever 287 is rotated the ear 292 is moved downwardly more nearly into the line between pivot pins 65 and 286. Thus, as the effect of the spring 293 would tend to increase by reason of its compression, this increase is compensated for by the decreasing moment arm through which the spring is acting. If some means were not provided for insuring that the effect of spring 293 remained substantially constant, the manual movement of lever 287 might, towards the end of such movement, result in the movement of lever 286 by reason of the movement of lever 287 being imparted through the spring 293. In the arrangement of the present invention, this is entirely avoided.

While I have shown certain specific embodiments of my invention for purposes of illustration, it is to be understood that the invention is limited only by the scope of the appended claims.

I claim as my invention:

1. In a control system comprising a heater having a fuel burner and a damper, a valve biased to closed position for controlling the flow of fuel to the burner, electrically operated power means associated with said valve for opening said valve, means operatively connected to said valve and having a portion projecting outwardly from the power means, said outwardly projected portion being connected to said damper to control the position of the damper in accordance with the position of the valve, and means including a strain release connection between the outwardly projecting portion of said previously named means and the portion connected to said valve to prevent manual opening of said valve by manipulation of said projecting portion of said previously named means.

2. In a control system comprising a heater having a fuel burner and a damper, a valve biased to closed position for controlling the flow of fuel to the burner, power means associated with said valve for opening said valve, means operatively connected to said valve and having a portion projecting outwardly from the power means, said

outwardly projected portion being connected to said damper to control the position of the damper in accordance with the position of the valve, means including a strain release connection between the outwardly projecting portion of said previously named means and the portion connected to said valve to prevent manual opening of said valve by manipulation of said projecting portion of said previously named means, and means for preventing opening of said valve by said power means when said strain release connection is extended.

3. In a control system comprising a heater having a fuel burner and a damper, a valve biased to closed position for controlling the flow of fuel to the burner, electrically operated power means associated with said valve for opening said valve, a cover enclosing said power means, means operatively connected to said valve and having a portion extending through said cover, said outwardly extending portion being connected to said damper to control the position of the same in accordance with the position of the valve, and means including a strain release connection between the portion of said previously named means outside of said cover and said valve to prevent manual opening of said valve by manual manipulation of the portion of said previously named means extending outside of said cover.

4. A motorized valve assembly for use in the control of a fluid fuel burning furnace having a damper, said assembly comprising a valve, a motor, means including a reduction gear train connecting said motor with said valve, a member connected with said valve and adapted to be connected to a damper for operating the same in accordance with movements of said valve, said member being connected to said valve through a strain release connection yieldable in valve opening direction whereby said valve can not be manually opened by actuation of said member, and means to prevent opening of said valve by said motor if said strain release connection is extended.

5. A motorized valve assembly for use in the control of a fluid fuel burning furnace having a damper, said assembly comprising a valve, a motor, means including a reduction gear train connecting said motor with said valve, a member connected with said valve and adapted to be connected to a damper for operating the same in accordance with movements of said valve, said member being connected to said valve through a strain release connection yieldable in valve opening direction whereby said valve can not be manually opened by actuation of said member, and means including a member projectable into the teeth of one of the gears of said gear train to prevent opening of said valve by said motor if said strain release connection is extended.

6. A motorized valve assembly for use in the control of a fluid fuel burning furnace having a damper, said assembly comprising a valve, a motor, means including a reduction gear train connecting said motor with said valve, a member connected with said valve and adapted to be connected to a damper for operating the same in accordance with movements of said valve, said member being connected to said valve through a strain release connection yieldable in valve opening direction whereby said valve can not be manually opened by actuation of said member, and means to prevent opening of said valve by said motor if said strain release connection is extended, said last named means comprising a lever

tiltable into the teeth of one of the gears of said gear train and a connection between said lever and said damper actuating member effective to tilt said lever when said member is moved independently of said valve.

5 7. In a control system comprising a heater having a fuel burner and a secondary air damper, a valve for controlling the flow of fuel to the burner, means biasing said valve to closed position, power means associated with said valve for opening said valve, means operatively connected to said valve and having a portion projecting outwardly from the power means, said outwardly projecting portion being connected to the secondary air damper to control the position of the damper in accordance with the position of the valve, and a strain release connection between said outwardly projecting portion of the previously named means and the portion thereof connected to said valve whereby manual opening of the valve by manipulation of said outwardly projecting portion is prevented, said strain release connection including the biasing means for the valve whereby said biasing means tends to hold 10 the two portions of the said previously named means in their normal relative positions as well as to move said valve to closed positions.

8. A motorized valve assembly for use in the control of a fluid fuel burning furnace having a damper, said assembly comprising a valve, a motor, means including a lever connecting said motor and said valve, a second lever connected to said first lever by a one-way strain release connection and adapted to be connected to a 15 damper for operating the same simultaneously with the valve, said strain release connection being yieldable only when a force is applied directly to said second lever in valve opening direction, and a single biasing means acting through said second lever and said strain release connection to hold said levers in their normal relative positions as well as to bias said valve to closed position.

9. A motorized valve assembly for use in the control of a fluid fuel burning furnace having a damper, said assembly comprising a valve, a motor, a reduction gear train having the high speed end thereof connected to said motor, a pivotally mounted lever pivotally connected to said valve and having a one way connection with the low speed gear of said gear train, a second lever connected to said first lever by a one way connection and adapted to be connected to a damper for operating the same simultaneously with the valve, said one way connection being yieldable when a force is applied directly to said second lever in valve opening direction, and a single biasing means acting through said second lever and said one way connection to hold said levers in their normal relative positions as well as to bias said valve to closed position.

10. A motorized valve assembly for use in the control of a fluid fuel burning furnace having a damper, said assembly comprising a valve, a motor, means including a lever connecting said motor and said valve, a second lever pivotally connected to said first lever, biasing means acting on said second lever on one side of said pivot point, said biasing means tending to move said lever in valve closing direction, and an abutment carried by said second lever on the other side of said pivot point and engaging said first lever in valve closing direction whereby the biasing means acts to urge said abutment against said first lever 15 and hence urge said valve towards closed posi-

tion and whereby movement of said second lever in valve opening direction imparts no movement to said valve.

11. A motorized valve assembly for use in the control of a fluid fuel burning furnace having a damper, said assembly comprising a valve, a motor, means including a lever connecting said motor and said valve, a second lever pivotally connected to the first lever, biasing means acting on said first lever to urge said valve towards closed position, an abutment on said second lever and adapted to engage said first lever in valve closing direction, and biasing means between said levers urging said second lever to assume a position relative to said first lever in which said abutment engages said second lever so that said levers normally move as a single unit but so that if said second lever is moved in valve opening direction, said biasing means yields to prevent such movement being transmitted to said first lever, the points at which said biasing means acts on said levers being relatively disposed so that the biasing means exerts a substantially constant force regardless of the relative position of said levers.

12. A motorized valve assembly for use in the control of a fluid fuel burning furnace having a damper, said assembly comprising a valve, a motor, a reduction gear train having the high speed end thereof connected to said motor, a pivotally mounted lever pivotally connected to said valve and to the high speed gear of said gear train, a second lever pivoted to said first lever at a point displaced from the pivot point of the first lever, and adapted to be connected to a damper for operating the same simultaneously with the valve, means for limiting the movement of said second lever with respect to said first lever in valve closing direction, biasing means acting on said second lever in valve closing direction to hold said levers rigid with respect to each other and to bias said valve to closed position, an element adapted to project into the teeth of one of the gears of said gear train, and a connection between said element and said second lever at the point of pivotal mounting of the first lever whereby when said levers are moved as a unit said element is not projected into the gear teeth but when said second lever is moved relative to said first lever, said element is so projected.

13. In a control system having condition changing apparatus and a plurality of control devices therefor, said control devices being movable from normal inactive positions to active positions, electrical motor means associated with a first of said devices for moving said device to its active position, a housing enclosing said motor means, means operatively connected to said first device and having a portion projecting outwardly through said housing and connected to said other control device, and means including a strain release connection between the outwardly projecting portion of said previously named means and the portion connected to said first control device to prevent manual movement of said first control device by manipulation of said projecting portion of said previously named means.

14. In a control system having condition changing apparatus and a plurality of control devices therefor, said control devices being movable from normal inactive positions to active positions, motor means associated with a first of said devices for moving said device to its active position, a housing enclosing said motor means,

- means operatively connected to said first device and having a portion projecting outwardly through said housing and connected to said other control device, means including a strain release connection between the outwardly projecting portion of said previously named means and the portion connected to said first control device to prevent manual movement of said first control device by manipulation of said projecting portion of said previously named means, and means for preventing movement of said first device by said motor means when said strain release connection is extended.
15. In a control system having condition changing apparatus and a plurality of control devices therefor, said control devices being movable from normal inactive positions to active positions, spring means biasing a first of said devices to its active position, motor means asso-

ciated with said first device for moving said device to its active position, a housing enclosing said motor means, means operatively connected to said first device and having a portion projecting outwardly through said cover and connected to said other control device, and means including a strain release connection between the outwardly projecting portion of said previously named means and the portion connected to said first control device to prevent manual movement of said first control device by manipulation of said outwardly projecting portion of said previously named means, said strain release connection including said spring means whereby said spring means tends to hold the two portions 10 of said previously named means in their normal relative positions as well as to bias said first device to its inactive position.

BENJAMIN CYR.

CERTIFICATE OF CORRECTION.

Patent No. 2,203,613.

June 4, 1940.

BENJAMIN CYR.

It is hereby certified that error appears in the printed specification of the above numbered patent requiring correction as follows: Page 4, first column, line 71, for the word "relative" read --relatively--; page 6, second column, line 32, for "assembly" read --assembling--; page 10, first column, line 19, claim 15, for "active" read --inactive--; and that the said Letters Patent should be read with this correction therein that the same may conform to the record of the case in the Patent Office.

Signed and sealed this 3rd day of September, A. D. 1940.

(Seal)

Henry Van Arsdale,
Acting Commissioner of Patents.
